UNITED STATES PATENT OFFICE.

EDWARD CARLSON, OF BUFFALO, NEW YORK, ASSIGNOR, BY MESNE ASSIGNMENTS, TO
REMINGTON RAND INC., OF NEW YORK, N. Y., A CORPORATION OF DELAWARE.

INDEX DEVICE.

Application filed January 31, 1925. Serial No. 6,146.

This invention relates to record or index-card or card-holder trays or supports on which a plurality of the cards or card-holders are arranged in overlapping relation.

The record cards, holders or devices, hereinafter called card holders, are usually provided with flaps at one edge between which and the body portion of the card holder the head of another holder may be inserted to maintain them in a nested series, with the body portions overlapping and lying substantially flatwise on the tray with their free edges exposed one beyond another in a plane substantially parallel with the tray bottom. The holders have lateral lugs or ears which engage beneath side flanges on the tray so that the holders are releasably connected thereto and may have sliding movements longitudinally thereon.

The trays have been provided with movable followers or members adapted to engage a portion of the tray and bear against an end card holder, usually between the body and the flap, to hold the card holders compactly in their nested relation. The follower is adapted to be actuated to move it to an inoperative position to release the card holders, so that one or more may be removed, or additional holders added to the series. For this purpose the followers have been made adjustable so that their holder-engaging portions may be moved forwardly or rearwardly to compensate for differences in the lengths of different series of holders.

The objects of the present invention are to construct a card index or record tray or support provided with an adjustable follower of improved and simplified construction; also to provide a combined follower and card-holder support; also to provide an improved operating device for the follower which is adjustable to position the combined follower and card-holder support in correct relation to series of holders of varying lengths, and which is so attached to the tray that the follower will be unaffected by the movement of the holders due to shocks which occur when the tray is moved into the cabinet.

Other objects are to provide a tray and follower which have interengaging parts for holding the follower in operative or

card-holding position, and also to provide the tray with a spring device adapted to automatically move the follower to its holder releasing position when the operating device is actuated.

Another object is to provide a follower and card-holder support which is pivotally connected to its operating stem or device so as to have a swinging movement relatively thereto to a position in which it uncovers the operating device and cooperating parts of the tray and renders these parts accessible for adjustment or inspection and at the same time bears on and holds the adjacent card holders positively in an inoperative position out of the way.

Another object is to construct an improved latch for trays of this sort which is adapted to engage a fixed part of the cabinet or tray support and releasably hold the tray in the cabinet.

Other objects are to improve and simplify card index trays and followers in the other respects hereinafter specified and claimed.

In the accompanying drawings, Fig. 1 is a plan view of a portion of a card index or record tray or slide embodying the invention.

Fig. 2 is a similar view thereof with the card holders thrown back to expose the follower or stop and adjacent parts.

Fig. 3 is a similar view showing the follower moved to its holder-releasing position.

Fig. 4 is a fragmentary plan view, broken away to show the adjusting means for varying the length of the follower-operating device.

Fig. 5 is a longitudinal section thereof on line 5—5, Fig. 4.

Fig. 6 is a plan view of the tray, similar to Fig. 2, but showing the card holder retaining plate and support swung to a position in which its operating device and adjacent parts are exposed.

Fig. 7 is a plan view, on an enlarged scale, of the front portion of the tray, with the follower-operating device in released position, and showing the means for moving it to this position when released from engagement with its locking or holding means.

Fig. 8 is a longitudinal vertical section of the tray on an enlarged scale, on line 8—8, Fig. 6.

Fig. 9 is a horizontal section on line 9—9, Fig. 8, showing the latch for releasably holding the tray in a cabinet.

Fig. 10 is a transverse vertical section 5 thereof on line 10—10, Fig. 9.

Figs. 11 and 12 are longitudinal vertical sections of the tray on an enlarged scale on line 11—11 and 12—12, Figs. 2 and 3 respectively.

10 Fig. 13 is a view similar to Fig. 7, showing the follower-operating device in holding position.

Fig. 14 is a transverse vertical section of the tray on line 14—14, Fig. 11.

15 Fig. 15 is a similar view on line 15—15, Fig. 12.

Fig. 16 is a view similar to Fig. 11 showing the operating member for the follower depressed preparatory to its movement to 20 releasing position.

The tray A or slide may be of any usual or suitable construction, (except as herein-after noted) adapted to receive a plurality of nested card holders B. The holders as 25 usual have body portions C and connecting hinged portions D by which they are attached to underlying flaps E at their upper edges, each holder being nested between the connecting portion and flap of an adjacent 30 holder. The flaps E are formed with lateral lugs or ears F for attaching the holders to the tray. The tray A includes a bottom plate or support 10 for the card holders, side walls 11 having inturned and depending 35 flanges 12 beneath which the lugs F of the holders are inserted, and a front or end wall 13. The tray also preferably has a back stop against which the rear holder of the series abuts to limit the extent to which 40 the holders may move rearwardly and which permits them to be compressed and maintained in their nested relation.

The combined follower and card-holder support embodied in the present invention 45 includes a substantially rectangular flat plate or member 20, adapted to extend beneath the body C of the front holder of the series with its rear edge 21 engaging between said body and the attached flap E. 50 This plate extends from side to side of the tray A between the side walls, its rear edge portion 21 being formed with a pair of lateral ears 22 adapted to slidably engage beneath the side flanges 12 so as to be guided 55 longitudinally in the tray. In its card holder retaining position the follower plate 20 inclines upwardly and forwardly with its front edge 24 adjacent the front wall of the tray, its front portion being supported 60 in this position by a fixed tray-bracing apron or member 25 secured in the tray and having an upper face or wall 26 which is inclined at the same angle as the plate 20 and forms a rigid rest therefor. The part 26 of 65 the apron 25 extends transversely between

the side flanges of the tray, and its front portion is provided with an offset attaching flange 27 the edge of which is transversely channelled at 28. This channel is adapted to be received and fits snugly in a complementary transverse and downwardly opening channel 29 formed along the top edge of the front wall 13 of the tray. The rear edge of the apron 25 is bent downwardly to form a vertical wall 30, the central portion of which is preferably cut away at 31 so as to leave two spaced wall parts, the lower edges of which are extended rearwardly to form a pair of feet or attaching portions 32 which rest on the bottom plate 10 of the tray. The apron 25 is attached to the tray by first inserting its channelled edge 28 in the channel 29 and then engaging the feet 32 with the tray bottom 10 and securing these feet thereto by suitable means such as spot-welding or riveting.

In accordance with the invention the follower plate 20 is provided with an operating member or actuating device of improved form which is pivotally secured thereto and is preferably adapted to be manipulated from the outside of the tray so that the follower may be moved from the card holder retaining position, Figs. 1 and 11, to its holder-releasing position, Figs. 3 and 12. The operating member is preferably made extensible so that it can be adjusted to position the front edge 21 of the follower in position to properly secure a greater or less number of holders. For this purpose the member includes a stem 35 extending longitudinally midway of the tray, and a sleeve or telescoping portion 36 into which the stem slidably fits and in which it is preferably releasably secured by a pin 37 on a finger piece 38 pivotally attached to the sleeve. The pin is adapted to enter hole 39 and any one of a series of holes 39 in the sleeve and stem respectively to vary the length of the operating device, the finger piece being lifted and swung laterally to permit the parts 35 and 36 to be adjusted. The operating device extends beneath the apron 25 and rearwardly beyond the same and is pivotally attached to the underside of the plate 20, preferably adjacent its rear edge, as by a hinge pin 40, and its stem portion 35 extends forwardly through a hole 41 in the front wall 13, where it is provided with a finger piece or knob 42 for actuating it. The finger piece is disposed close to the face of the front wall and prevents rearward movements of the follower, and a lug or projection 43 formed on the stem at the inner side of the tray is adapted to prevent unintentional outward movements of the follower, as by engaging the offset flange 27 of the apron 25, an aperture 44 being formed in the apron through which the lug extends. The stem 35 is yieldingly held with its lug

43 in engagement with the flange 27, and may be depressed to disengage said lug to permit the operating device to be moved forwardly and thereby move the follower to its releasing position. The yielding means for this purpose comprises a bowed wire spring 45 loosely arranged in a retainer or part 46 formed of sheet metal, and which has a vertical transverse wall 47 adjacent the front wall of the tray, said wall having a narrow top flange 48 extending rearwardly and from which depends a pair of spaced lugs 48 between which and the wall 47 the intermediate bowed portion of the spring 45 is disposed. The end portions of the spring are held between the wall 47 and a pair of lugs 50 which are turned up from a bottom flange 51 of the retainer, said flange being secured to the bottom plate 10 of the tray to hold the retainer rigidly in place. The extremities of the spring are bent rearwardly and bear on the flange 51. By bearing on the finger piece 42 and depressing the spring 45 the stem 35 may be moved forwardly, as the hole 41 is wide or deep enough to permit the passage of the lug 43 therethrough.

The tray is preferably provided with means for automatically moving the follower to its card holder releasing position when the stem 35 is depressed as stated, these means, as shown in the drawings preferably comprising a spring member 55, see Figs. 7 and 13, which is detachably maintained in position on the underside of the apron 25 and has an intermediate part 56 extending behind and engaging a hook 57 stamped out of and depending from the stem 35 of the follower-operating device. The ends of the spring are disposed on opposite sides of the stem and are detachably engaged with integral hooks 58 on the apron, and the parts of the spring between the ends and the intermediate portion 56 are bowed, as at 59, these portions being stressed or under tension when the operating device is in its inner position so as to hold the lug 43 firmly against its stop. When the stem is depressed the lug is released from the tray and the operating device and follower will be moved outwardly to the holder-releasing position by the spring 55. This movement is limited by the front ends of a pair of parallel depressed spring-guiding webs or parts 60, formed by stamping out and depressing portions of the apron 25, see Figs. 13 and 16. To insure the proper movement of the follower outwardly, and prevent it from catching on the front wall or adjacent parts of the tray, the front edge 24 of the follower plate is bent upwardly whereby this edge is guided over the tray front.

The described construction of the follower and cooperating parts of the tray provides a

practical structure adapted to positively maintain the nested holders in their intended position in the tray, and also provides a firm and smooth rest for the front holders so as to maintain their free edges in alignment with the edges of the other holders. The operating member is so connected to the tray that the follower is always positively held in its adjusted position and can not move rearwardly due to the momentum caused by shocks imparted to the tray when in use; also rearward movements of the card holders and the reaction thereof to such movements cannot displace or disconnect the follower. The follower plate, being pivotally connected to its operating device as described, is capable of being swung about its pivot so as to extend rearwardly as shown in Fig. 8, to permit access to the operating device and other parts normally concealed beneath it and in which position it bears on the adjacent card holders and holds them out of the way.

The tray of the present invention is also provided with an improved latch or retainer for releasably holding the tray in its closed position in the cabinet and preventing the tray from accidentally sliding outwardly, as for instance, should the cabinet be tipped forwardly while being carried or lifted.

This latch, see Figs. 8-10 comprises a transverse, horizontally disposed, flexible plate or strip 62 secured at one end on the top face of the tray bottom 10, as by means of a pair of lugs 63 struck out of said bottom and one of which passes through an aperture 64 in the plate, and are clinched down on the plate to hold this end thereof rigidly in place. The opposite end portion of the plate 62 is provided with a depending catch or stop portion 65, preferably of U-shaped transverse section which projects through a hole in the tray bottom 10 and the bottom portion of which inclines upwardly and rearwardly so that its rear edge 66 is substantially flush with the tray bottom. The front face of the stop 65 is adapted to engage a retaining part on the cabinet, such as the flange X of the partition on which the tray is supported when not in use. To release the tray the plate is provided with a finger piece 67 which projects forwardly through a hole 68 in the front wall of the tray and which is adapted to be engaged by a finger of the user to lift the latch and move the stop out of engagement with the flange X. In its rearward movements into the cabinet the inclined lower face of the stop 65 acts as a cam to guide the stop over the partition X.

In the use of the tray, the stop 65 may often be subjected to violent shocks by suddenly striking the retaining part on the cabinet especially after the finger piece has been manipulated to lift the latch, and to prevent

the latch 62 from being bent backwardly or otherwise injured from such blows, an abutment or reinforcement 69 is formed on the bottom plate 10 of the tray directly back of the stop 65. This abutment projects upwardly and is adapted to engage the rear edge of the latch to brace it and prevent the same from moving rearwardly.

The tray of the present invention is also provided with a handle or pull 70 of suitable form and the finger piece 67 of the latch 62 is preferably arranged below and within this handle, so as to be easily manipulated to release the tray at the time the handle is grasped to draw the tray forward.

I claim as my invention:

1. In a record tray or slide adapted to support a series of record holders flatwise thereon in overlapping and nested relation, the combination of a follower having a holder-engaging portion adapted to engage an end holder of said series so as to compress and maintain said holders in their nested relation, an operating member movably attached to said holder-engaging portion and engaging a fixed part on said tray to maintain said follower in operative position, said operating member being releasable from said fixed tray part, and yielding means on said tray engageable with said operating member and which is adapted to move said follower to its holder-releasing position when said operating member is released from said fixed tray part.

2. In a record tray or slide adapted to support a series of record holders flatwise thereon in overlapping and nested relation, the combination of a follower having a holder-engaging portion adapted to engage an end holder of said series so as to compress and maintain said holders in their nested relation, an operating member movably attached to said holder-engaging portion and engaging a fixed part on said tray to maintain said follower in operative position, said operating member being releasable from said fixed tray part, and a spring member mounted on said tray and bearing against a part on said follower and which is under compression when said operating device is in engagement with said fixed tray part, said spring member being adapted to extend when said operating device is released from said fixed tray part so as to move said follower to its holder-releasing position.

3. In a record tray or slide adapted to support a series of record holders flatwise thereon in overlapping and nested relation, the combination of a follower having a holder-engaging portion adapted to engage an end holder of said series so as to compress and maintain said holders in their nested relation, an operating member movably attached to said holder-engaging portion and engag-

ing a fixed part on said tray to maintain said follower in operative position, said operating member being releasable from said fixed tray part, a transverse apron fixed in and adapted to brace said tray and adjacent to which said operating member is disposed, a spring member connected to said fixed apron and having a part engaging said operating device so as to compress said spring when said operating device is in engagement with said fixed tray part, and said spring member being adapted to extend when said operating device is released from said fixed tray part to positively move said follower to its holder-releasing position.

4. In a record tray or slide adapted to support a series of record holders flatwise thereon in overlapping and nested relation, the combination of a follower having a holder-engaging portion adapted to engage an end holder of said series so as to compress and maintain said holders in their nested relation, an operating member movably attached to said holder-engaging portion and engaging a fixed part on said tray to maintain said follower in operative position, said operating member being releasable from said fixed tray part, a transverse apron fixed in and adapted to brace said tray and adjacent to which said operating member is disposed, a bowed spring member having its ends connected to parts on said apron and its intermediate portion engaging a part on said operating device so as to compress the bowed portions of the spring when said operating device is in engagement with said fixed tray part, and said bowed spring being adapted to extend when said operating device is released from said fixed tray part to positively move said follower to its holder-releasing position.

5. In a record tray or slide adapted to support a series of record holders flatwise thereon in overlapping and nested relation, the combination of a follower having a holder-engaging portion adapted to engage an end holder of said series so as to compress and maintain said holders in their nested relation, an operating member movably attached to said holder-engaging portion and engaging a fixed part on said tray to maintain said follower in operative position, said operating member being releasable from said fixed tray part, a transverse apron fixed in and adapted to brace said tray and form a support for the front portion of said follower whereby said follower is adapted to support the body portions of the adjacent card holders, said operating member extending longitudinally beneath said apron and said apron having a spring device connected thereto which is provided with a part engaging said operating member so as to hold said spring under compression when said oper-

ating device is in engagement with said fixed tray part, and said spring device being adapted to positively move said follower to its holder-releasing position when said operating device is released from said fixed tray part.

6. In a record tray or slide adapted to support a series of record holders flatwise thereon in overlapping and nested relation, 10 the combination of a follower having a plate of substantially the size of the record holder bodies and which is adapted to be disposed beneath and support the body portions of adjacent card holders and having a rear 15 edge adapted to engage an end holder of the series to compress said holders and maintain them in their nested relation, an operating member extending beneath said plate and connected thereto and having a part engaging a fixed part on said tray to maintain 20 said plate in its operative position and from which it is releasable to permit said plate to be moved to its holder-releasing position.

7. In a record tray or slide adapted to 25 support a series of record holders flatwise thereon in overlapping and nested relation, the combination of a follower having a plate of substantially the size of the card holder bodies and which is adapted to be disposed beneath and support the body portions of adjacent card holders and having a rear edge 30 adapted to engage an end holder of the series to compress said holders and maintain them in their nested relation, an operating member 35 extending beneath said plate and connected thereto, said operating member having a part engaging a fixed part on said tray to hold said follower in operative position and having means for adjusting said plate 40 longitudinally of said tray to position said follower in correct holding relation to holder series of different lengths.

8. In a record tray or slide adapted to support a series of record holders flatwise thereon in overlapping and nested relation, 45 the combination of a follower having a plane imperforate plate of substantially the size of the card-holder bodies, and which is adapted to be disposed beneath and support the body portions of adjacent card holders and having a rear edge adapted to engage an end holder of the series to compress said 50 holders and maintain them in their nested relation, an operating member extending longitudinally beneath said plate, a transverse hinge connection between said follower 55 and operating member, said operating member being adapted to engage a fixed part on said tray to maintain said follower in operative position and being releasable from said fixed part to permit the follower to move to its holder-releasing position, and said hinge connection being adapted to permit said follower plate to swing to a rearwardly extending inoperative position when 60

said operating device is released to permit access to said operating device.

9. In a record tray or slide adapted to have a series of record holders arranged thereon in overlapping and nested relation, 70 said tray having an end wall and a follower disposed adjacent said end wall and having a holder-engaging portion adapted to engage an end holder of said series to maintain said holders in their nested relation, an 75 operating device connected to said follower and having a part releasably engaging a fixed part on said tray to hold said follower in operative position and an actuating part extending outwardly through said end wall, a 80 spring member mounted on said tray and adapted to yieldingly engage and hold said operating device against said fixed tray part and said operating device being adapted to be depressed to flex said spring member and release said device from said fixed tray part. 85

10. In a record tray or slide adapted to have a series of record holders arranged thereon in overlapping and nested relation, 90 said tray having an end wall, and a follower disposed adjacent said end wall and having a holder-engaging portion adapted to engage an end holder of said series to maintain said holders in their nested relation, an operating device connected to said follower and having a part releasably engaging a fixed part on said tray to hold said follower in operative position, and an actuating part extending outwardly through said end wall, a 95 retainer fixed on said tray, a spring member arranged therein and having a portion yieldingly engaging said operating device to hold it against said fixed tray part, said device being adapted to be depressed to flex said spring member and release said device 100 from said fixed tray part. 105

11. In a record tray adapted to support a series of record holders flatwise thereon in overlapping and nested relation, the combination of a follower having a holder-engaging section adapted to engage an end holder of said series so as to compress and maintain said holders in their nested relation, and an operating member movably attached to said holder-engaging section and engaging a fixed part on said tray to maintain said follower in operative position, said operating member being releasable from said tray so as to move said holder-engaging section to holder-releasing position. 110

12. In a record tray adapted to support a series of record holders flatwise thereon in overlapping and nested relation, an operating member associated with said tray, a follower having a holder-engaging section 115 movably associated with said operating member, and spring means associated with said operating member and adapted to maintain said operating member and follower in holder-engaging position, said op- 120 125 130

erating member and follower being adapted for reciprocation longitudinally of said tray to holder-releasing position.

13. In a record tray having an end wall and adapted to support a series of record holders flatwise thereon in overlapping and nested position, an operating member extending beyond said end wall so as to form an actuating member outside of said wall, a follower having a holder-engaging section movably associated with said operating member, latch means associated with said operating member and tray wall adapted to maintain said holder-engaging section in contact with a record holder, and spring means adapted to cause said operating member to move away from said record holders when said actuating member is actuated.
14. In a record tray having an end wall and adapted to support a series of record holders flatwise thereon in overlapping and nested position, an apron fixed near said end wall, a follower having a holder-engaging section, and an operating member movably connected to said section and slidably ad-

justable relative to said apron and adapted to releasably maintain said holder-engaging section in contact with a record holder.

15. In a record tray having an end wall and adapted to support a series of record holders flatwise thereon in overlapping and nested position, a follower having a holder-engaging section, and an operating member movably connected to said section and slidably adjustable relative to said end wall and adapted to releasably maintain said holder-engaging section in contact with a record holder.

16. In a record tray having an end wall and adapted to support a series of record holders flatwise thereon in overlapping and nested position a follower having a holder-engaging section, and an operating member adjustable in length connected to said section and slidable relative to said end wall, and adapted to releasably maintain said holder-engaging section in contact with a record holder.

EDWARD CARLSON.
